UNITED STATES PATENT OFFICE.

CHARLES W. DIPPERT, OF KENMORE, NEW YORK.

APPARATUS FOR USE IN ASSEMBLING RADIATOR CORES.

Application filed July 22, 1926. Serial No. 124,269.

This invention relates to improvements in apparatus or devices for use in assembling radiator cores and more particularly for use in assembling radiators of the fin and tube type. The apparatus is particularly applicable to assembling a radiator core of this kind in which crimped or formed fins are used, but may also be advantageously used in assembling cores in which straight or flat fins are used.

The objects of this invention are to provide an apparatus of this kind which is so formed that the fins of a radiator core may be quickly and easily placed into their correct relations relatively to each other and supported in such relation while the tubes are passed through the alined holes in the fins; also to provide an apparatus of this kind which is so constructed that the core when assembled may be quickly and easily removed from the apparatus; also to provide an apparatus of this kind with means cooperating with configurations of formed or crimped radiator fins for holding such fins in their correct positions for passing the tubes through the holes in the fins; also to improve the construction of apparatus of this kind in other respects hereinafter specified.

In the accompanying drawings, Fig. 1 is a side elevation of a radiator core assembly apparatus embodying this invention.

Fig. 2 is a sectional, plan view thereof on line 2—2, Fig. 1.

Fig. 3 is a fragmentary, detailed section thereof on an enlarged scale on line 3—3, Fig. 1.

Fig. 4 is a fragmentary, sectional plan view of the apparatus, on an enlarged scale, showing in one portion of the figure a sectional plan of the apparatus below the tubes of the core, and in the other portion a sectional plan thereof above some of the tubes, one of the tubes being shown partly inserted through the fins.

Fig. 5 is a fragmentary, transverse, sectional elevation thereof on line 5—5, Fig. 1.

Fig. 6 is a fragmentary, end view of the upper portion of one side of the apparatus showing the parts in a position to facilitate the removal of the core from the apparatus.

Fig. 7 is a fragmentary, longitudinal section of the upper portion of the apparatus

showing the relation between the fins and tubes of a radiator and the supporting and positioning means for the fins.

Fig. 8 is a fragmentary, top plan view thereof with the fins of the core arranged in place thereon.

Fig. 9 is a fragmentary, sectional elevation thereof on line 9—9, Fig. 7.

Fig. 10 is a fragmentary, face view of a fin of a radiator core in connection with which the apparatus may be used.

Fig. 11 is a fragmentary view of the rear edge of the fin.

Fig. 12 is a fragmentary front edge view thereof.

It is well known that a fin or tube type of radiator in which the fins are crimped or formed into different shapes possesses a number of advantages over a similar type of radiator in which the fins are straight, but the assembling of radiators with crimped fins has caused considerable difficulties, particularly when the adjacent fins of the radiator are not provided with interfitting surfaces, but contact only at points or lines of contact, and the formation of interfitting surfaces is undesirable since this reduces the radiating capacity of the fins. The apparatus embodying this invention may be used equally well in connection with the assembling of radiator cores in which the fins are formed or crimped in such a manner that they contact only along points or lines of contact, or in connection with the assembling of radiator cores in which the fins are of other construction or form.

The apparatus embodying my invention is so constructed that the fins required for a radiator core of a certain size are placed in correct relation to each other so that the holes for the tubes of the radiator are alined, and the apparatus also supports the fins in such a manner that the tubes may be inserted endwise through the holes in the fins while they are held on the apparatus. The apparatus is preferably also so constructed that the radiator core when completely assembled is released from some of the guide or positioning means for the fins, so that the assembled cores can easily be removed from the apparatus. In the particular construction shown I provide a support which may be in the form of a plate or platform against which the edges of the fins may rest for alin-

ing either the front or rear edges of the fins of a radiator core, and a plurality of guide members which the faces of the fins engage for holding the fins in their correct relation to each other while the fins are positioned on the apparatus and while the tubes are inserted through the holes in the fins. The support for alining the edges of the fins may, if the apparatus is used in connection with formed or crimped fins, be provided with parts engaging with the crimps or contour of the fins. Since these crimps or contours are in fixed relation to the holes in the fins, these parts serve to aline the holes in the fins. 15 In the apparatus illustrated the support or platform is movable to strip the assembled core from the guide members.

In the particular embodiment of the invention illustrated the frame of the apparatus includes a fixed top plate A which may be suitably supported in any desired manner, for example by means of upright legs or supports a, and the fixed top plate or member A is provided at its edge portion 25 with downwardly extending flanges a' to which the legs a are secured. The guide members for use in positioning and spacing the radiator fins relatively to each other are secured to the top frame member A, these 30 guide members in the particular form illustrated being a series of upright pins or posts B having enlarged heads b at their lower ends and being secured in holes in the fixed plate A, for example by a drive fit. C represents the plate, platform or support on which the edges of the fins of the core rest during the assembling of the core, and this support is provided with holes or openings through which the upright guide members 35 or pins B pass. The guide pins or posts B are arranged in rows extending both longitudinally and transversely of the apparatus, the radiator fins being positioned between transverse rows of guide pins and the tubes 40 being passed through the alined holes in the fins between longitudinal rows of guide pins. The fin supporting plate C is movable vertically, in the particular construction shown, relatively to the upright pins or guide members B. 45

50 Any suitable or desired means may be used for moving the support or platform C relatively to the pins to strip the assembled core from the pins or posts B, it being obvious that many different devices could be used for producing this relative movement.

60 In the construction shown, the support or platform C is slidably mounted on the frame of the apparatus by means of a plurality of upright slide rods or bars 15 secured to the support C and guided in suitable bearing 65 lugs 16 in the top plate A of the apparatus,

and in lower lugs 17 arranged near the lower portions of the opposite side flanges a' of the stationary top of the apparatus, and each of the slide rods 15, in the particular construction illustrated, is provided with rack teeth 70 18 adapted to engage with gears or pinions 19 mounted on shafts 20, the ends of which are suitably journalled in bearings or lugs 21 which may also be formed in the opposite side flanges a' of the top plate or member A. 75 Two shafts 20 are shown, each of which is provided with two pinions 19, and means of any suitable kind may be provided for simultaneously turning the two shafts 20 so that all of the four guide rods 15 of the movable support C may be raised and lowered simultaneously. For this purpose one or two sprocket chains 25 may be employed which mesh with sprockets 26 mounted on the shafts 20, so that rotary motion on either 80 shaft is transmitted to the other shaft in the same direction. Either one of the two shafts may be turned by means of a crank or handle 27 secured on one of the shafts and adapted to be turned by hand for imparting rotation to the shafts, and vertical movement to the slide rods or racks 15. 85

The crank or handle 27 is preferably provided with an arm 28 provided at its end with a spring pressed latch or bolt 29, see 90 Fig. 3, adapted to engage in a hole or recess 30 formed in one of the side walls or flanges a' of the stationary top plate A, a spring 31 normally holding the bolt 29 in its locking position in the hole 30, as shown in Figs. 100 2 and 3. 32 represents a knob or enlargement of the bolt 29 by means of which the bolt may be pulled by hand against the action of the spring 31 to permit the crank 27 to be turned. The object of the locking bolt is to hold the fin supporting plate or platform C in its upper position while the core is being removed, the plate C remaining normally in its lowered position by gravity, as shown in Fig. 1. This locking device for 105 the crank or handle 27 may be entirely omitted or replaced by any other suitable type of locking or holding device. 110

The pins or guide members B may be of any suitable or desired shape, depending entirely upon the nature of the fins of the radiator core in connection with which this apparatus is to be used, and a larger or smaller number of guide members or pins may be employed depending upon the number of radiating fins to be used in a core. In the particular construction shown, the apparatus is intended to be used in connection with fins such as illustrated in Figs. 8 to 12, which fins D are formed or crimped so that the front edges thereof form diamond-shaped openings through which the air enters into the radiator core. For this purpose the front edge d of each pin is of angular zig-zag form as shown in Fig. 12 and the 115 120 125 130

fins are so assembled that the points or angles of the edges of one fin lie against or approximately meet the points or angles of an adjacent fin to form the diamond shaped air inlet passages in the radiator, and in the particular construction shown the rear edges d' of these fins are substantially straight. Parts of the intermediate portions d^2 of the radiator fins are bent approximately into the same plane as the straight back edges thereof so as to engage the sides of the pins or guide members B. The radiator fins are also provided with the usual holes d^3 through which the water tubes E of the radiator extend. A radiator of this kind is described in my Patent No. 1,014,816 but it will be understood that the apparatus may be used in connection with radiators having fins of many different forms or construction, and the holes d^3 for the water tubes may be either round as shown, or in case tubes of elongated cross section are used, the holes d^3 should correspond to the shape of the water tubes.

In case a radiator assembly apparatus is used in connection with straight or flat fins, the pins or guide rods B may be placed closer together so that only one fin may be inserted between each pair of rods or guide members B, and in such a case the holes in the fins can easily be alined by alining the sides of the fin by any suitable straight edge or surface. However, if the front edges of the radiator fins are formed or crimped to produce air passages at the front of the radiator of such shapes as diamonds, squares, hexagons or others, a pair of fins is placed between each transverse row of guide pins or devices B, and other means are provided for correctly positioning the fins relatively to each other so as to aline the holes therein. In the particular form shown a plurality of comparatively short studs F are provided on the support or platform C, which are so arranged that the studs fit into the bent front edges of the fins and thus assure the correct alining of adjacent fins, the upper ends of the studs F being preferably tapered so that the edges of the fins will readily slide into their correct positions. These studs are arranged in rows extending both transversely and longitudinally of the support C and these rows are arranged between the rows of guide members or posts B. The studs or projections F are comparatively short and are below the holes in the fins so that the studs do not interfere with the placing of the tubes into the holes in the fins.

In the use of the apparatus described, the fins D are placed into their correct positions between the upright posts or guide members B, two fins of the construction shown being placed between each post and the fins being oppositely arranged to form air passages between adjacent fins. The fins are preferably

placed on the apparatus with their front faces downwardly, so that the front zig-zag edges of the fins will cooperate with the studs F to correctly position the fins, as shown in Figs. 8 and 9 and to aline the holes therein. After the required number of fins have been so positioned on the apparatus, the holes d^3 thereof will all be alined so that the tubes E can be inserted endwise through the fins, this being done either by hand or by some implement for forcing a group of tubes in the direction of their length through the alined holes d^3 . If the tubes are placed into the fins by hand, a spacing plate G, Fig. 4, is preferably employed which may be placed between two transverse rows of guide posts or pins B and against which the ends of the tubes E may abut to stop the further movement of the tubes through the fins. After all the tubes have been placed into their operative positions in the fins, the crank 27 is released by drawing out the knob 32 and disengaging the bolt 29, whereupon the two shafts 20 are turned by means of the crank 27, thus causing the four slide rods 15 and the movable support C to be raised to strip the assembled core from the posts or guide members B. Upon returning the crank 27 to its original position, the apparatus is ready for the assembling of another core. It will be understood that during the vertical movement of the edge supporting platform or member C, the upright guide posts or members B slide through the holes in the member C. Fig. 6 shows the position of the parts when the edge supporting platform or member C is in its upper position in which position the core is ready to be lifted from the apparatus.

I claim as my invention:

1. An apparatus for use in assembling fin and tube radiator cores, including a support for one edge of each fin, and a plurality of guide members adapted to cooperate with the faces of said fins for positioning the fins in correct alinement for the insertion of tubes therethrough.

2. An apparatus for use in assembling fin and tube radiator cores, including a support for one edge of each fin, and a plurality of guide members adapted to cooperate with the faces of said fins for positioning the same in correct alinement for the insertion of tubes therethrough, said support and guide members being movable relatively to each other to move said guide members out of engagement with said fins.

3. An apparatus for use in assembling fin and tube radiator cores, including a support for one edge of each fin, and a plurality of guide members adapted to cooperate with the faces of said fins for positioning the same in correct alinement for the insertion of tubes therethrough, said guide members

being spaced apart to permit tubes to be inserted through holes in said fins and between guide members.

4. An apparatus for use in assembling fins of radiator cores, including a support for one edge of each fin, means on said support for guiding said edge of each fin in its correct relation to other fins, and guide members extending above said support for guiding the portions of said fins above said support and supporting the same in their correct relations to each other. 70

5. An apparatus for use in assembling fins of radiator cores, including a support for one edge of each fin, a plurality of guide members between which the fins are inserted edgewise and which are adapted to cooperate with parts of said fins for positioning the same correctly relatively to each other, and means for moving the assembled core out of engagement with said guide members. 80

6. An apparatus for use in assembling fin and tube radiator cores including a plurality of guide members spaced apart in one direction to permit radiator fins to be placed edgewise between said guide members, and in another direction to permit radiator tubes to be inserted through alined holes in the fins placed between said guide members. 85

7. An apparatus for use in assembling fin and tube radiator cores including a plurality of guide members spaced apart in one direction to permit radiator fins to be positioned between said guide members, and in another direction to permit radiator tubes to be inserted through alined holes in said fins, and means for removing an assembled core from said guide members. 95

8. An apparatus for use in assembling fin and tube radiator cores including a plurality of guide members spaced apart in one direction to permit radiator fins to be positioned between said guide members, and in another direction to permit radiator tubes to be inserted through alined holes in said fins, and means independent of said guide members for positioning the fins to aline holes in said fins for the insertion of tubes therethrough. 105

9. An apparatus for use in assembling fins of radiator cores, including a support adapted to be engaged by edges of the fins of the radiator, means for positioning said edges in correct relation to each other, guide members extending through openings in said support and adapted to engage the faces of said fins for holding said faces in correct relation to each other, and means for moving said guide members out of engagement with said fins when the radiator core is assembled. 115

10. An apparatus for assembling fins of radiator cores, the combination of a support on which edges of the fins of said cores are adapted to be placed, means on said support for alining said fins relatively to each 125

other, and guide members extending through said support into an operative position to engage the sides of said fins, and means for drawing said guide members out of engagement with said radiator fins when the radiator core is assembled. 130

11. In an apparatus for use in assembling radiator cores of the fin and tube type having formed fins, the combination of a support with which one edge of each fin is adapted 75 to engage, means on said support cooperating with formed portions of the fin for positioning the fins relatively to each other to aline holes in said fins, and guide members extending through said support and having parts adapted to engage with parts of the 80 faces of said fins for holding said fins in substantially parallel relation to each other, said guide members being spaced apart to permit the insertion of tubes through the 85 alined holes of said fins, and means for producing relative movement between said guide members and said support to permit the assembled radiator core to be withdrawn out of engagement with said guide members. 90

12. In an apparatus for use in assembling radiator cores of the fin and tube type having formed fins, the combination of a support having means for engaging one edge of each fin, means on said support 95 adapted to enter between adjacent fins and to cooperate with the configurations formed in the fins to position the fins relatively to each other to aline the holes therein, guide members extending through said support 100 and adapted to engage the sides of the fins and between which the fins may be placed to guide the same into correct relation to the fin support, and means for withdrawing said guide members out of engagement with said 105 fins.

13. In an apparatus for use in assembling radiator cores of the fin and tube type having formed fins, the combination of a support having a surface adapted to engage one edge of each fin, projections on said support extending above said surface and adapted to enter between adjacent fins and to cooperate with configurations formed in said fins to 110 aline said fins in the direction of their lengths, guide members for holding said fins in substantially parallel positions relatively to each other and arranged to permit the insertion of tubes through the alined holes in 115 said fins. 120

14. In an apparatus for use in assembling radiator cores of the fin and tube type, the combination of a platform having a surface adapted to be engaged by one edge of each fin, a plurality of posts extending through apertures in said platform and adapted to cooperate with the faces of said fins to position the same correctly relatively to each other, and means for producing relative movements between said platform and said 125 130

posts to withdraw said posts from engagement with said radiator fins.

15. In an apparatus for use in assembling radiator cores of the fin and tube type, the combination of a platform adapted to support one edge of each fin, and a plurality of posts extending through apertures in said platform, said posts being arranged in rows extending both lengthwise and transversely of said apparatus, said posts being spaced apart to permit the insertion of fins between transverse rows of said posts, and to permit the insertion of tubes through alined holes in said fins between longitudinal rows of said posts.

16. In an apparatus for use in assembling radiator cores of the fin and tube type, the combination of a platform adapted to support one edge of each fin, a plurality of posts extending through apertures in said platform, said posts being arranged in rows extending both lengthwise and transversely of said apparatus, said posts being spaced apart to permit the insertion of fins between transverse rows of said posts, and to permit the insertion of tubes through alined holes in said fins between longitudinal rows of said posts, and means for holding said fins in position in which the holes therethrough are in alinement.

17. In an apparatus for use in assembling radiator cores of the fin and tube type, the combination of a platform adapted to support one edge of each fin, a plurality of posts secured to said apparatus and extending through apertures in said platform and adapted to cooperate with the faces of said fins to hold the same in operative relation to each other, and means connected to said platform for moving said platform relatively to said posts to move an assembled radiator core out of engagement with said posts.

18. In an apparatus for use in assembling radiator cores of the fin and tube type, the combination of a platform adapted to support one edge of each fin, a plurality of posts secured to said apparatus and extending through apertures in said platform and adapted to cooperate with the faces of said fins to hold the same in operative relation to each other, a plurality of rack bars con-

nected with said platform and gears for moving said rack bars to move said platform relatively to said posts to withdraw an assembled radiator core out of engagement with said posts.

19. In an apparatus for use in assembling radiator cores of the fin and tube type, the combination of a platform adapted to support one edge of each fin, a plurality of posts secured to said apparatus and extending through apertures in said platform and adapted to cooperate with the faces of said fins to hold the same in operative relation to each other, a plurality of rack bars connected with said platform and gears for moving said rack bars to move said platform relatively to said posts to withdraw an assembled radiator core out of engagement with said posts, and means connecting said gears for moving all of said gears simultaneously to move said platform relatively to said posts.

20. In an apparatus for use in assembling fin and tube radiator cores having crimped fins, the combination of means for alining the longitudinal edges of the fins, means for holding said fins in substantially parallel planes, and means cooperating with crimped portions of said fins for positioning the fins to aline the holes therein.

21. In an apparatus for use in assembling fin and tube radiator cores having crimped fins, the combination of means for alining the longitudinal edges of the fins, means cooperating with crimped portions of said fins for positioning said fins to aline the holes therein, and means for holding said fins in substantially parallel planes and supporting said fins while tubes are passed through said holes in the fins.

22. An apparatus for use in assembling fins of radiator cores, including a support for one edge of each fin, a plurality of guide members adapted to cooperate with parts of said fins for positioning the fins relatively to each other, means for producing relative movement between said support and guide members to strip an assembled core from said guide members, and means for locking said support and guide members against relative movement.

CHARLES W. DIPPERT.
